Application October 20, 1937, Serial No. 72,338
In Great Britain July 20, 1937

Term of patent 7 years

To all whom it may concern:

Be it known that I, Gerald Spencer Barrett, a British subject, residing at 36 Wendover Court, Park Royal, Acton, London, W. 3, England, have invented a new, original, and ornamental Design for a Projection Lamp for Use in Cinema Studios, of which the following is a specification, reference being had to the accompanying drawing, forming part thereof.

Fig. 1 is a front view of a projection lamp for use in cinema studios;

Fig. 2 is a side view; and

Fig. 3 is a back view, showing my new design.

I claim:

The ornamental design for a projection lamp for use in cinema studios, substantially as shown.

GERALD SPENCER BARRETT.
